FIRE ESCAPE

Francis Edward Rose, Drexel Hill, Pa.

Application November 24, 1947, Serial No. 787,703

6 Claims. (Cl. 254—151)

1

The present invention relates in general to fire escape devices, and more particularly to fire escapes of the type adapted to occupy a small area within the rooms of a building near exterior openings in the wall thereof, and adapted to individually lower persons suspended from the device from the exterior opening to the ground at a safe rate of descent.

Emergency fire escapes for public buildings of several floors height, particularly hotels and large professional buildings, capable of providing auxiliary means for the occupants of the buildings to reach the ground from the upper floors of the building safely, normally are of the suspended ladder type mounted along the sides of the buildings and permanently or pivotally positioned to provide communication for the occupants from one floor to the other or progressively to the ground. These types, however, because of the large space along the side of the building occupied, must be limited in number on any single wall of the building, requiring that persons desiring to use such fire escapes must proceed to central points on any given floor by the internal passages through the building to gain access to the fire escape, rendering such fire escapes inaccessible to some of the occupants of the building should any of the internal building passages be blocked by fire or other means, even though the rooms occupied by such occupants may at that time not be immediately threatened by the fire. Use of such types of fire escapes is also unpopular because of the unsightliness of the ladder devices suspended alongside the exterior walls of the buildings.

Due to the large number of fatalities resulting from fires in public buildings, provided with the conventional types of fire escapes permanently suspended along the walls of the buildings, due apparently to the occupants of the buildings finding the access passages to the fixed fire escapes blocked, and thus being denied any safe means of reaching the ground from the upper floors of such buildings, the need for some type of individual fire escape capable of being retained ready for use in a small space and of relatively small cost outlay, has become apparent, so that such units may be provided in each room or near each external exit or opening of the building in readiness for use from that point.

Accordingly, an object of the present invention is the provision of a novel fire escape device capable of being contained within a small space ready for use to individually lower persons suspended

2

therefrom from an exterior opening in the wall of a building to the ground.

Another object of the present invention is the provision of a novel fire escape unit normally containable in a small space ready for use to permit a plurality of such units to be mounted adjacent exterior openings of a building, which units are capable of lowering individually, persons suspended from the unit to the ground level without injury.

Another object of the present invention is the provision of a novel fire escape unit of such character as to permit a plurality of such units to be disposed adjacent the exterior upper floor openings of a building and capable of automatically lowering persons suspended therefrom from such upper floor openings to the ground at a controlled decelerating rate of descent.

Another object of the present invention is the provision of a novel fire escape unit normally of such size to permit the units to be conveniently disposed internally of the building adjacent each upper floor external opening of the building walls ready for use, and capable of automatically lowering persons suspended therefrom from such openings to a level near the ground at a controlled decelerating rate, and substantially abruptly increasing the rate of deceleration from such level near the ground over the remaining descent to the ground level.

Other objects, advantages and capabilities of the invention will become apparent from the following description, taken in conjunction with the accompanying drawings, showing only a preferred embodiment of the invention.

In the drawings:

Figure 1 is a perspective view of a fire escape unit embodying the present invention, showing the fire escape disposed in a housing permanently mounted below an exterior window of a building;

Figure 2 is a vertical longitudinal section view of the fire escape unit and housing, taken along the lines 2—2 of Figure 1; and

Figure 3 is a vertical transverse section view of the fire escape unit and housing, taken along the lines 3—3 of Figure 2.

The present invention in general comprises drum means having a stepped core of at least two different diameters mounted for rotation on a horizontal axis within housing means, governor means operatively coupled to the drum means, through speed reduction gearing means, for maintaining the speed of rotation of the drum means constant when torque is applied to the drum means, and cable means wound upon and

secured to the stepped core of the drum means having harness means disposed on the free end thereof adapted to fit over and suspend a person from the line and the drum means coupled thereto, the drum and governor coupled thereto permitting the cable to be played out at a decreasing rate on application of torque to the drum when a person is suspended from the cable until the cable is wound off of the drum to the diameter of the larger portion of the core, after which further unwinding of the drum produces a substantially abrupt reduction in the amount of cable payed out per revolution of the drum and a corresponding abrupt decrease in the rate of descent of the persons suspended from the cable. When the length of the cable for the unit is adjusted to substantially equal the distance from the window or opening with which the unit is associated to the ground less approximately five feet, a person suspended in the harness may be lowered at a constantly decelerating rate of descent from the window to a point near the ground, and then automatically brought almost to a stop, by reason of the reduced diameter drum, with no danger of injury due to shock from abrupt contact with the ground at the lower end of the cable.

The invention will be more fully understood from the following detail description of the drawing, in which like reference characters designate corresponding parts throughout the several figures. All the components of the fire escape unit are adapted to be normally disposed in a housing 10 forming a receptacle adapted to be secured to the side wall 11 of a room adjacent the exterior window, indicated at 12, either to the side of or immediately beneath the window 12, to render the unit readily accessible for immediate use to permit safe escape. A similar device will be provided for each exterior window of the building, each occupying little space and obviating the necessity of a large number of unsightly ladder-type fire escape structure to handle the same number of persons adequately. The housing 10 is formed of a vertically disposed base plate member 13 having holes 14 at the four corners thereof to receive mounting bolts 14' to secure the base 13 to the wall 11, a sheet metal member extending outwardly and then upwardly from the bottom of the base plate 13 to form the bottom 15 and front 16 of the receptacle housing 10. At one side of the receptacle, a pair of spaced metal plates 17 and 18, forming brackets, are secured to the base plate 13 to extend perpendicularly to the base plate 13 in parallel vertical planes, the outer of the two plates 17 forming one of the ends of the receptacle and the spaced pair 17 and 18 forming mounting brackets for the drum means and a portion of the reduction gear train to be later described. The inner plate or bracket 18, together with a sheet metal end plate 19 and horizontal partition 20 form a closed compartment for the gear train.

The ends 17 and 19 for the receptacle housing 10 are disposed inwardly from the lateral edges of the base plate 13 and the holes 14 therein to leave a mounting flange at each end of the unit. The sheet metal members forming the sides and ends of the receptacle housing 10 may be turned at their adjacent edges to provide flange faces, as indicated at 21, to be secured flush with the surface of the adjoining member as by brazing or welding. A sheet metal cover or top 22 is pivotally secured to the ends 17 and 19 by means of pivot pins 23 through turned edges 24 of the

cover 22, along a horizontal axis adjacent the top edge of the front 16 of the housing 10, permitting the cover to open from the rear or adjacent the base plate 13.

5 Mounted within the compartment defined by the brackets 17 and 18 to rotate on a horizontal axis, is a drum or spool member, generally indicated at 25, formed of a stepped core 26 of substantially cylindrical configuration having a larger diameter portion 27 and a smaller diameter portion 28 secured to a shaft 29 journaled in journal boxes 30 and 30' disposed in the brackets 17 and 18, respectively, and a pair of disk members 31, 31' forming sides for the spool member 25 secured to the ends of the core 26. A cable 32 formed of wire or substantially fire-proofed fiber rope of small diameter and sufficient strength to support a load greater than the weight of any person who may employ the device, is secured to the core 25 at one end of the smaller diameter portion 28, and wound around the smaller core section 28 until the coil of cable becomes of the diameter of the larger core portion 27, after which the cable is wound progressively across the entire length of the core 26 between the sides 31, 31', of the drum member 25. Appropriate harness means 33, such as a rope loop or other means adapted to fit over the body of the person to be lowered thereby and conveniently couple him to the cable 32, is formed at the free end of the cable and when the cable is fully wound about the drum 25, is disposed in the portion of the housing 10 overlying the partition 20 and below the cover 22.

35 The components for controlling the speed of rotation of the drum 25 when unwinding the cable 32 therefrom to lower the person suspended in the harness 33, are all housed in the compartment formed by bottom 15 of housing 10, horizontal partition 20, and the vertical plates 18 and 19. 40 A bevel gear 35 is keyed or otherwise rigidly secured on the shaft 29 to rotate with the drum 25, and is provided with peripheral teeth angularly disposed thereon to engage the teeth on a bevel gear 36 mounted to rotate freely on a shaft 37 fixed to journal plate 38 secured to the bottom 15 of the housing 10 and flush therewith. A tubular shaft 39 is likewise disposed in the shaft 37, and is integral with both the bevel gear 36 and a gear 40 to transmit torque from the bevel gear 35 to the gear 40. An idler gear 41 mounted on a stub shaft 42, is intercoupled between the spur gear 40 and a spur gear 43 mounted on a shaft 44 journaled for rotation between mounting plate 38 and an upper mounting plate 45 secured to the horizontal partition 20. A substantially larger diameter spur gear 46 is likewise fixed to the shaft 44 to engage a small diameter gear 47 on shaft 48, likewise journaled for rotation in the mounting plates 38 and 45 having a corresponding spur gear 49 fixed thereon, coupled with a gear 50 mounted on governor shaft 51 journaled in the mounting plates. The governor is of typical centrifugal governor construction, comprising a heading member 52 fixed to the shaft 51 and having diametrically opposed radial slots 53 therein, through which pivot pins 53' are disposed to pivotally couple governor arms 54, 54' thereto. The governor arms 54, 54' have weights 55 mounted on the free ends thereof to draw the arms into radially extending position approaching the horizontal plane through their pivots, due to centrifugal force acting thereon as the speed of rotation of the shaft 51 is increased. The inner or pivoted ends of the arms 54, 54' are provided with in-

wardly disposed eccentric cam surfaces adapted to abut against the inner surface of the slots 53 when the orientation of the arms 54, 54' reaches a predetermined angle to limit further upward movement of the arms and thus to effect regulation of the speed of the governor shaft 51 and the drum shaft 29 positively coupled therewith, to maintain the speed of rotation of all positively coupled components constant in the adjusted governor speed.

Thus the torque generated in the shaft 29 when the drum 25 is rotated by the weight of the person suspended from the cable 32, will be transmitted through the bevel gears 35 and 36, and spur gears 40, 41 and 42, to shaft 44, thence through gears 46 and 47 to shaft 48, and through intercoupled gears 49 and 50 to the governor shaft 51 and arms 54, 54', so that sufficient drag is imposed by the centrifugal force generated during rotation of the governor and applied to the speed reduction gearing network from the governor to the drum 25 to maintain the speed of the drum shaft 25 constant, the speed of descent of the cable 32 therefore progressively decreasing due to the constant reduction in effective diameter of the drum 25, as the cable 32 is unwound therefrom.

Operation of the device is thus rendered duly automatic and safe. The person employing the fire escape device need only put on the harness 33, kept readily available lying on the horizontal platform 20 underneath the cover 22, and lower himself from the sill of the exterior window of the building from which he desires to escape, the drum 25 defining the coil of cable 32 unwinding under the force of the weight of the person suspended from the cable 32, and the speed of rotation of the drum shaft 29 being maintained constant through the regulatory action of the governor and the train of speed reduction gear coupled between the drum 25 and the governor. The speed of rotation of the shaft 29 being maintained constant, there will be a progressive deceleration of the rate of descent of the bottom end of the cable 32, and the harness 33, due to the progressively reducing diameter of the coil of cable 32 on drum 25. This deceleration occurs in accordance with the unwinding of layers of the cable 32 rather than with each revolution of the drum 25, so that the average rate of descent is markedly increased after the coil of cable unwinds down to the diameter of the large diameter portion 27 of the drum core 26, the smaller width of the small diameter core portion 28 on which the remainder of the cable 32 is wound, of the order of only several diameters of cable in width, requiring only a few revolutions of the shaft 29 to unwind one layer of cable, and the length of cable per layer payed out on rotation of the drum at this portion being considerably less than that toward the outer portion of the drum. This will be effective to so reduce the speed of descent of the person suspended from the cable as he nears the ground as to progressively stop all descent with substantially no shock to the passenger.

It will be apparent from the above description that a novel fire escape device capable of safely lowering persons individually from a building opening without injury to the person from abrupt changes in rate of descent, and adapted to be employed in large numbers in any convenient small space available near exterior openings in the building, has been devised, this device being particularly adaptable for use in large numbers in existing building structures to provide adequate individual escape facilities.

While but one particular embodiment of the invention has been particularly shown and described, it is distinctly understood that the invention is not limited thereto, but that various modifications may be made therein without departing from the spirit and scope thereof, and it is desired, therefore, that only such limitations shall be placed thereon as are imposed by the prior art and are set forth in the appended claims.

- 10 Having thus described my invention, I claim:
1. A fire escape device adapted to safely lower persons from the upper floors of buildings to the ground, comprising drum means mounted for rotation and having a stepped core of at least two different diameters, cable means secured to said core and adapted to be coupled at its free end to the person to be lowered, said cable being wound in progressive layers about the smaller diameter portion of said core forming a coil of the diameter of said larger diameter portion of said core and then wound by layers over the total length of said core forming a coil surrounding and contiguous with said first mentioned coil, and means operative to maintain the speed of rotation of said drum means substantially constant.
  2. A fire escape device adapted to safely lower persons from the upper floors of buildings to the ground comprising, drum means mounted for rotation and having a stepped core of at least two distinct diameters, cable means secured to said core and adapted to be coupled at its free end to the person to be lowered, said cable means being wound in progressive layers about said core forming a coil from the smaller diameter portion to the larger diameter portion of said core, and a second coil surrounding and contiguous with the first mentioned coil extending over the whole core, and means coupled with said drum means operative to maintain the speed of rotation of said drum means constant.
  3. A fire escape device adapted to automatically lower persons from the upper floors of buildings at a decelerating rate of descent over a substantial initial portion of the travel of the person and producing a material substantially abrupt increase in the rate of deceleration over the latter portion of said travel, comprising drum means mounted for rotation on a horizontal axis and having a stepped core of at least two distinct diameters, cable means secured to said core and adapted to be secured at its free end about the person to be lowered, said cable being wound in progressive layers about the smaller diameter portion of said core until the diameter of the coil formed thereby is equal to the larger diameter portion of said core and then about said coil and the remaining portion of said core, and governor means coupled to said drum means for maintaining the speed of rotation of said drum means substantially constant.
  4. A fire escape device adapted to automatically lower persons from the upper floors of buildings at a periodically decelerating rate of descent as the person nears the ground and producing a safe, substantially abrupt increase in the rate of deceleration at a point substantially adjacent the ground, comprising drum means mounted for rotation on a fixed horizontal axis and having a stepped core of at least two distinct diameters, a cable secured to said stepped core and having harness means at the free end of said cable for readily securing the cable about the person to be lowered, said cable being wound in progressive layers about said core forming a coil from the smaller diameter portion to the larger diameter

portion of said core, and a second coil surrounding and contiguous with the first mentioned coil extending over the whole core, and governor means coupled to said drum means operative to maintain the speed of rotation of said drum means substantially constant.

5. A fire escape device for safely lowering persons individually from the upper floors of buildings to the ground comprising, housing means forming a receptacle for the components of said device having mounting means associated therewith for securing said housing means to an internal wall of a building adjacent an exterior opening in said wall, drum means disposed in said housing mounted for rotation on a horizontal axis and having a stepped core of at least two distinct diameters, cable means secured to said core and adapted to be coupled at its free end about the person to be lowered, said cable means being wound in progressive layers about said core forming a coil from the smaller diameter portion to the larger diameter portion of said core, and a second coil surrounding and contiguous with the first mentioned coil extending over the whole core, and means coupled with said drum means operative to maintain the speed of rotation of said drum means constant.

6. A fire escape device for safely lowering persons individually from the upper floors of a building to the ground comprising, housing means forming a receptacle for the components of the device adapted to be mounted on an inner wall

of the building immediately below a window therein, bracket means within said housing positioning a horizontal shaft on which drum means is rotatably mounted, said drum means having a stepped core of two distinct diameters, a cable secured to the smaller diameter portion of said core and having harness means formed at the free end thereof adapted to couple the cable about the person to be lowered, said cable being wound in progressive layers about said core forming a coil from the smaller diameter portion to the larger diameter portion of said core, and a second coil surrounding and contiguous with the first mentioned coil extending over the whole core, and governor means within said housing coupled through speed reduction gearing means to said drum means operative to maintain the speed of rotation of said drum means constant.
